(57) **CLAIM**

The ornamental design for paper clip and pen holder, as shown and described.

DESCRIPTION

FIG. 1 is a perspective view of paper clip and pen holder showing my new design;

FIG. 2 is a front elevational view thereof;

FIG. 3 is a rear elevational view thereof;

FIG. 4 is a left side elevational view thereof;

FIG. 5 is right side elevational view thereof;

FIG. 6 is a top view thereof;

FIG. 7 is a bottom view thereof;

FIG. 8 is a second perspective view thereof; and,

FIG. 9 is a third perspective view thereof.

The paper clips in FIG. 8 and the paper clips, pen and paper in FIG. 9 depicted by means of broken lines have been shown for illustrative purposes only and form no part of the claimed design.
